GLASS WASHER

Robert W. Orr, Union, Ohio

Application September 28, 1948, Serial No. 148,807

Term of patent 7 years

(Cl. D9—2)

To all whom it may concern:

Be it known that I, Robert W. Orr, a citizen of the United States, residing at Union, in the county of Montgomery and State of Ohio, have invented a new, original, and ornamental Design for Glass Washers, of which the following is a specification, reference being had to the accompanying drawings, forming a part thereof.

In the drawings:

Fig. 1 is a side elevational view of a glass washer, showing my new design.

Fig. 2 is a plan view of same.

I claim:

The ornamental design for a glass washer, as shown.

ROBERT W. ORR.
